UNITED STATES PATENT OFFICE.

FRANCIS A. REICARD, OF BROOKLYN, NEW YORK.

HAT-HOLDER.

SPECIFICATION forming part of Letters Patent No. 268,937, dated December 12, 1882.

Application filed October 17, 1882. (No model.)

To all whom it may concern:

Be it known that I, FRANCIS A. REICARD, of the city of Brooklyn, in the county of Kings and State of New York, have invented a new and Improved Hat-Holder, of which the following is a full, clear, and exact description.

The object of my invention is to provide a new and improved device for holding a hat, which device is adapted to be attached to the rear side of the back of a chair or any other suitable article.

The invention consists in the combination, with a chair, of a hat-holding device attached to the rear side of the back of the chair.

15 The invention also consists in a hat-holding device formed of two disks, having rubber coverings on the inner surfaces, and pressed against each other by a spring or a spring-hinge.

20 The invention also consists in a hat-holding device formed of two disks having rubber coverings on the inner surfaces, pressed against each other by a rubber band passed through apertures in the disks, and held to the same by cross-pieces passed through the ends of the elastic band.

25 Reference is to be had to the accompanying drawings, forming part of this specification, in which similar letters of reference indicate corresponding parts in all the figures.

30 Figure 1 is a side elevation of a chair having my improved hat-holder attached to the rear side of its back. Fig. 2 is a front elevation of my improved hat-holder. Fig. 3 is a cross-sectional elevation of the same.

35 Two disks or plates, A B, of wood, celluloid, or other suitable material are hinged to each other near the edges, and are pressed toward each other by a spring. The lower parts of the inner surface of each plate or disk A B is covered with a layer, C, of rubber. The disk A is provided with an aperture, D, through which a screw or bolt is passed into or through the back F of a chair, so that the said disk A will be secured on the rear surface of the back of the chair, or the device can be attached to a hat-board, post, &c.; but it is specially adapted to be attached to the back of a chair. The

disks can be hinged together in any suitable manner, and any suitable spring can be used 50 to press them together. I prefer to provide each disk with an aperture, G, through which an elastic band, H, is passed, through the ends of which transverse rods or pins J are passed, which are contained in transverse grooves in 55 the outer surface of the disks. The hinge and the disk will thus be formed in one. The rim of a hat, K, is passed between the parts of the disks covered with rubber, the disks having been previously separated to admit passing 60 the hat-rim between them, which rim is pressed and held between the disks as soon as the same are released. The rubber C prevents the hat-rim from sliding from between the disks.

The above-described device does not injure 65 the rim of any hat, and permits of withdrawing the hat-rim without injury to the same.

If a hat-holder is attached to the back of a chair in a church, theater, concert-hall, &c., it will be out of the way, as it is above the knees 70 of the person sitting in the chair behind the one to which the hat is held.

Cloth, felt, &c., can be used in place of rubber for coverings on the inner surfaces of the disks.

75 Having thus described my invention, what I claim as new, and desire to secure by Letters Patent, is—

1. A hat-holder made, substantially as herein shown and described, of two hinged disks 80 pressed against each other by a spring, and having rubber coverings on their inner sides, substantially as herein shown and described, and for the purpose set forth.

2. The combination, with the disks A B, having rubber coverings on the inner surfaces, of the elastic band H, passed through apertures in the said disks, and of the transverse pieces or pins J, passed through the ends of the elastic band, substantially as herein shown and 90 described, and for the purpose set forth.

FRANCIS A. REICARD.
